FUEL FEED FOR INTERNAL COMBUSTION ENGINES

Franklin W. Gamage and Franklin T. Gamage,
Indianapolis, Ind.

Application July 22, 1933, Serial No. 681,686

12 Claims. (Cl. 123—198)

- It is the object of our invention to produce a locking mechanism for use in association with an internal combustion engine such as an automobile engine. More specifically, it is our object to produce such a locking mechanism which will permit operation of the engine for a limited time after the mechanism has been locked and will then, after the expiration of such limited time, render the engine inoperative.
- 5 In applying our invention to an internal combustion engine using liquid fuel, we provide between the engine and the main fuel-supply tank an auxiliary tank which, during normal operation of the engine, is maintained full. Our locking mechanism, in its preferred form, includes means for interrupting the supply of fuel to this auxiliary tank and also includes a float-controlled switch responsive to the fuel-level in the auxiliary tank. Such float-operated switch is connected in series or is otherwise associated with the ignition circuit of the automobile so that it will open the ignition circuit of the engine after a predetermined quantity of fuel has been withdrawn from the auxiliary tank. Our invention 10 also includes a second switch which is manually controlled, preferably jointly with the means controlling the supply of fuel to the auxiliary tank, such second switch being connected in parallel with the float-operated switch and being closed under normal conditions but opened when the device is operated to interrupt the supply of fuel to the auxiliary tank.
- The accompanying drawings illustrate our invention: Fig. 1 is a diagrammatic view illustrating our invention as applied to an engine in which the fuel is supplied from a more or less remote tank to the engine by a fuel pump; Fig. 2 is a diagrammatic illustration showing our invention in association with an engine in which 15 the fuel-supply is effected through the medium of the well-known vacuum tank; Fig. 3 is a modification of our invention in which a different arrangement is employed to control the supply of fuel to an engine in which fuel is pumped from the supply tank; Fig. 4 is an axial section through the joint switch and fuel-controlling means; Fig. 5 is a transverse section on the line 5—5 of Fig. 4; and Fig. 6 is a vertical axial section through the auxiliary fuel-tank.
- 20 In the arrangement illustrated in Fig. 1, where our invention is associated with an engine in which fuel is supplied to the carburetor by a pump, the auxiliary tank 10, which will be described in detail hereinafter, is connected in the supply line of the pump so that the fuel sup-
- plied to the engine flows through the auxiliary tank. The lockable means for controlling fuel flow takes the form of a valve which, when locked, vents the auxiliary tank thus providing an air-bleed in the suction line of the pump and preventing the supply of further fuel to the auxiliary tank. Should the engine be operated after the valve is locked, the fuel withdrawn from the auxiliary tank will cause a drop in the fuel level therein, which will result, as indicated above, in 10 the opening of the float-controlled switch, and this in turn will open the ignition circuit and stop the engine.
- When our invention is embodied in an engine to which fuel is supplied by a vacuum fuel-feed system, as shown in Fig. 2, the auxiliary tank 10 may be connected between the elevated vacuum tank and the carburetor of the engine and the lockable valve disposed between the vacuum tank and the auxiliary tank to cut off the supply 15 of fuel to the auxiliary tank when the valve is locked.
- The arrangement illustrated in Fig. 3, like that shown in Fig. 1, is adapted for use with an engine in which fuel is supplied by a pump. Here, the auxiliary tank 10 is connected to the float-bowl of the carburetor of the engine in such a way as to increase the effective capacity of the float bowl. The lockable valve, which in this instance is a simple two-way valve, is located at 20 any convenient point in the line through which fuel is supplied to the carburetor.
- In all modifications illustrated, the float-controlled switch is associated directly with the auxiliary tank 10 to be responsive to the fuel-level 25 therein and is connected in the ignition circuit. Jointly operable with the fuel-controlling valve is a second switch which is connected in parallel with the float-operated switch so that the ignition circuit can be completed even if the float-operated switch is open.
- The auxiliary fuel tank which finds application in various embodiments of our invention and which is illustrated in Fig. 6 comprises a tank-body 10 having a cover 11. Upon the cover 11, which is conveniently of insulating material, there is mounted a float-controlled electrical switch which may take the form of two stationary contacts 12 and 13 adapted to be bridged 30 by a movable contact 14. A spring 15 acting upwardly on the movable contact 14 serves normally to hold it in engagement with the fixed contacts 12 and 13 to complete an electrical connection between them.

Within the tank 10 we provide a float 16 which may be rigidly mounted upon a rod 17 that extends upwardly through the cover 11 into association with the movable contact 14. Conveniently, 5 the movable contact 14 is mounted upon a member 14' of insulating material through which the rod 17 projects, and the upper end of the rod is provided with a head 18 which, when the float 16 drops below a predetermined point, engages the 10 member 14' and moves it downwardly to disengage the movable contact 14 from the fixed contacts 12 and 13, and thereby to interrupt the electrical connection between them.

A housing 20 mounted upon the cover 11 may 15 be provided to enclose the switch mechanism. Wires 21 and 22 are connected respectively to the contacts 12 and 13 and extend through the wall of the housing 20 to be connected as hereinafter set forth.

20 At or near its bottom, the tank 10 is provided with an outlet connection 25. The bottom of the tank may also include a clean-out or drain plug 26 provided at its inner end with an upwardly extending sleeve 27 which serves as a guide for 25 the slidable rod 17. The upper end of the rod 17 may be guided by a sleeve 28 which projects downwardly from the cover 11.

In its side wall, the tank 10 is provided with 30 a fluid connection 30, the purpose of which will hereinafter be set forth.

In addition to the connections 25 and 30 we may in certain instances provide a third connection 31 for the tank 10. This connection is located near the top of the tank, and its communication 35 with the interior of the tank is arranged to be controlled by the float 16. To this end, the connection 31 may communicate with a downwardly opening central port in the sleeve 28, and the rod 17 may be provided with a valve member 40. 32 adapted to close this port when the float 16 is in its upper position and to open the port whenever the float drops.

The combined valve and switch which we employ in our invention may take several forms, 45 one of which is illustrated in Figs. 4 and 5. In such construction, the valve has a body 35 in which is mounted a rotatable valve plug 36. The plug 36 has portions which project on opposite sides of the valve body 35, and on one of such 50 projecting portions there is mounted a switch arm 37 adapted, when in one position, to effect an electrical connection between two fixed contacts 38 and 39. On the side opposite the switch-arm 37 the valve plug is operatively connected to the 55 rotatable element of a cylinder-lock 40 or other suitable lock in such a way that the switch arm 37 and valve plug can only be controlled by an authorized individual having a key to the lock 40.

The valve 35-36 may be either a simple shut-off valve or a three-way valve, depending upon 60 the precise use to which it is to be put. In the three-way valve illustrated in Figs. 4 and 5, the valve body 35 is provided with diametrically opposite ports adapted respectively for connection 65 to conduits 41 and 42 and with a third port 43 which communicates with the atmosphere. The rotatable valve-plug 36 has two controlling positions in one of which, indicated in full-lines in Fig. 5, communication between conduits 41 and 70 42 is effected while the port 43 is closed and in the other of which, indicated in dotted lines, the conduit 42 is connected to the port 43 and the port communicating with the conduit 41 is closed. The passages in the plug 36 and the switch-arm 75 37 are so angularly disposed that when the con-

duits 41 and 42 are interconnected the switch 37-38-39 will be closed.

The auxiliary tank shown in Fig. 6, and the combined valve and switch illustrated in Figs. 4 and 5 may be used in various ways. When used 5 in association with an engine having a fuel-pump, the arrangement illustrated in Fig. 1 may be employed. In this arrangement, the engine 50 has an engine-operated fuel pump 51 which delivers the liquid fuel to a carburetor 52 in which the 10 fuel is mixed with air and supplied to the engine through the usual intake manifold 53. In associating our locking mechanism with such an engine the connection 30 of the auxiliary tank 10 is connected to a fuel-supply tank 55 which may be more or less remote from the engine. The connection 25 at the bottom of the tank 10 leads to the inlet of the pump 51. The pipe 41 from the valve casing 35 is connected to the intake 15 manifold 53 of the engine, or other suitable suction passage, and the conduit 42 leads to the connection 31 of the tank 10.

The ignition system of the engine, of which only the ignition coil 56 is shown, is connected to the usual battery 57 through the switch 37- 25 38-39 and also through a second switch 58 which may be the usual ignition switch for the engine and may or may not be key-controlled. The float-operated switch, as indicated above, is connected in parallel with the switch 37-38-39. 30

The position of the valve plug 36 and the switch-arm 37 illustrated in Fig. 1 are those respectively occupied by such elements when our locking mechanism is locked. If it be assumed that the engine has not been operated following 35 the locking of the valve-plug 36 and switch-arm 37 in the respective positions shown in Fig. 1, the auxiliary tank 10 will be full and the float-controlled switch 12-13-14 will be closed. It will therefore be possible, by merely closing the 40 switch 58, to render the engine operative. However, if the engine is operated under such circumstances, the first fuel withdrawn from the auxiliary tank 10 will cause a lowering of the float 16 and of the valve member 32, thus causing 45 the tank 10 to be vented to atmosphere through the conduit 31-42 and the port 43. The resultant air-bleed thus effected prevents the pump 51 from drawing any fuel from the tank 55 to maintain the fuel-supply in the auxiliary tank 50 10; and as the engine continues to operate, the fuel-level in the auxiliary tank 10 will drop until the switch 12-13-14 is open, thus rendering the ignition circuit of the engine incomplete and stopping the engine. 55

When an authorized individual desires to operate the engine after it has been stopped as just described, the lock 40 is unlocked and the valve plug 36 and switch-arm 37 rotated through 90° in a clockwise direction to close the port 43, and to interconnect the contacts 38 and 39 in the ignition circuit. This makes it possible to complete the ignition circuit by closing the switch 58, and thereby the engine may be placed in operative condition. 60

It is a characteristic of fuel pumps used in automobile engines that they will pump no more fuel than is required to maintain the float bowl of the carburetor full. Unless special provision were made, therefore, the fuel level in the auxiliary tank 10, after having once been lowered, would never be raised. It is because of this that we provide the conduit 41 which, when the valve plug 36 and switch arm 37 are in normal or unlocked position, connects the intake manifold 53 65 70 75 75

with the upper portion of the auxiliary tank 10. As a result of this arrangement, the reduced pressure obtaining in the intake manifold 53 when the engine is being operated is transmitted 5 to the auxiliary tank and results in drawing fuel from the supply tank 53 into the auxiliary tank at a more rapid rate than such fuel is withdrawn by the pump 51. This causes the fuel-level in the tank 10 to rise until the valve member 32 10 engages its seat at the bottom of the sleeve 28 and closes the communication between the tank and the intake manifold. When this occurs, normal operating conditions are restored, and the engine may continue to operate indefinitely 15 under the control of the ignition switch 58.

Fig. 2 illustrates the arrangement employed when our invention is to be embodied with an engine supplied with fuel by the vacuum fuel-feed system. In this arrangement there is provided a vacuum tank 60 of any convenient and well-known construction, such vacuum tank being located above the carburetor 52 so that fuel can flow from it to the carburetor under the influence of gravity. The vacuum tank, as is 25 usual, has a suction connection 61 to the intake manifold 53 and a supply connection 62 leading to the supply tank 55. As before, the conduit 42 from the valve 35 is connected to the connection 31 of the auxiliary tank 10 and the discharge connection 25 of such tank is placed in communication with the carburetor 52. The connection 41 of the valve 35 leads to the discharge opening of the vacuum tank 60. The electrical connections are the same as those illustrated in Fig. 1. 35 The connection 30 of the tank 10 is not used, and may be closed by a cap 65.

As in Fig. 1, the lock-controlled valve and switch are shown in locked position in Fig. 2. Under these circumstances, the switch 37—40 38—39 is open, the conduit 41 is closed, and the conduit 31—42 communicates with the atmosphere through the valve-port 43. If the engine has just been stopped, the auxiliary tank 10 will be full, and the float-controlled switch 12—45 13—14 closed. As in the case of the arrangement illustrated in Fig. 1 the engine, if now placed in operation, will withdraw fuel from the tank 10, the supply in which can not be replenished because of the closing of the conduit 41. 50 Eventually, as above described, the float-operated switch 12—13—14 will be opened and the engine stopped.

To restore the system to operative condition after it has been stopped as just set forth, the 55 lock 40 is unlocked and the valve-plug 36 and switch-arm 37 rotated 90° in a clockwise direction. This operation closes the valve-port 43, interconnects the contacts 38 and 39 in the ignition circuit, and interconnects the conduits 41 and 42 in the fuel-supply line. When the engine 60 is now placed in operation, the supply of fuel in the auxiliary tank 10 is replenished by fuel supplied from the vacuum tank 60, the float 16 rises, and the spring 15 closes the switch 12—13—14. 65 This places the system in condition for normal operation.

Like Fig. 1, Fig. 3 illustrates an arrangement in which our invention is associated with an engine having a fuel-pump. The electrical connections are the same as those employed in the 70 modifications of our invention shown in Figs. 1 and 2. The lock-controlled valve 35—36', however, which may be a simple two-way valve, is connected at any convenient point in the conduit 75 65 through which fuel is supplied from the

supply tank 55 to the carburetor 52. The auxiliary tank 10 is disposed adjacent the float bowl 66 of the carburetor 52 and connected thereto so that the fuel-levels in the tank and the float bowl will be substantially the same. The connection 30, above the fuel level in the tank, is 5 open to atmosphere to provide an air vent similar to that found in the usual carburetor float-bowl. In this arrangement, the connection 31 on the auxiliary tank is not needed and may be 10 eliminated.

As is evident, the tank 10 merely serves to increase the effective capacity of the float bowl 66.

In Fig. 3, the valve 35—36' and the switch 15 37—38—39 are shown in locked position, the valve being closed and the switch being open. Since the valve 35—36' prevents any fuel being supplied from the tank 55, any operation of the engine will result in a lowering of the common 20 fuel-level in the auxiliary tank 10 and float bowl 66. After a predetermined quantity of fuel has been withdrawn from the tank 10 and float bowl 66 the float-controlled switch 12—13—14 will 25 be opened to open the ignition circuit and stop the engine.

An authorized individual desiring to start the engine after it has been so stopped will unlock the lock 40 and rotate the valve plug 36' and switch arm 37 through 90° to open the valve 30 and close the switch 37—38—39. This closing of the switch makes it possible to complete the ignition circuit by closing the ignition switch 58 if it is not already closed, and the engine may 35 then be started. The fuel-supply line 65 being open, the pump 51 refills the auxiliary tank 10 and float bowl 66 causing the float 16 to rise and the switch 12—13—14 to close, thus restoring normal operating conditions.

It will be apparent from what has been set 40 forth above that all modifications of our invention permit a temporary or limited operation of the engine when the locking mechanism has been locked. This makes it possible for the owner of an automobile to place it in a public garage 45 and, by locking the locking mechanism, insure that while the automobile may be moved around within the garage to any necessary extent, it can not be taken from the garage and driven indefinitely by unauthorized individuals. Our invention is also useful in preventing theft of an automobile to which it is applied, since the automobile can not be driven indefinitely unless the fuel-supply connections are rearranged. It is 50 true that after the engine has been stopped by 55 the opening of the switch 12—13—14 it would be possible to restore it to operating condition merely by bridging the wires 21 and 22 with a suitable electrical connection; but this alone will not provide for the maintenance of a fuel-supply in the auxiliary tank 10, and the automobile can only be driven until such fuel-supply 60 is exhausted.

By varying the distance between the position occupied by the head 18 on the rod 17 when 65 the auxiliary tank 10 is full and the movable switch-member 14—14', the extent to which an automobile could be operated after having been locked can be varied at will. We think it advisable to dispose the head 18 so that an automobile equipped with our invention could be 70 driven about a mile or somewhat less after having been locked. This would permit the locked automobile to be driven as might be necessary in a public garage. 75

We claim as our invention:

1. In combination, an internal combustion engine having a carburetor and an ignition system, means for supplying fuel to said engine, an auxiliary fuel tank, a switch in the ignition circuit of said engine, mechanism responsive to the level of fuel in said auxiliary tank for opening said switch when such fuel-level drops below a predetermined point, lock-controlled means for 10 limiting the fuel supplied said engine to fuel withdrawn from said tank, and a lock-controlled switch connected in parallel with said first-named switch.
2. The invention set forth in claim 1 with the 15 addition that a single lock controls jointly both said fuel-limiting means and said lock-controlled switch.
3. In combination, an internal combustion engine having a carburetor and an ignition system, 20 means for supplying fuel to said engine, an auxiliary fuel tank, lock-controlled means for limiting the fuel supplied said engine to fuel withdrawn from said tank, and mechanism operative to render said ignition system inoperative upon 25 the withdrawal of a predetermined quantity of fuel from said tank.
4. In combination with an internal combustion engine having an ignition system, means for supplying fuel to said engine, a device actuatable to 30 render said ignition system inoperative, a control member, and mechanism operable under the control of said control member and responsive to the amount of fuel used by the engine for actuating the device which renders the ignition system inoperative.
5. In combination with an internal combustion engine, means for supplying fuel to said engine, a device actuatable to render the engine inoperative, a control member, and mechanism operable 35 under the control of said control member and responsive to the amount of fuel used by said engine for actuating the device which renders the engine inoperative.
6. In combination with an internal combustion engine having an ignition system, means for supplying fuel to said engine, a device actuatable to 40 render said ignition system inoperative, mechanism responsive to the amount of fuel used by the engine for actuating the device which renders the ignition system inoperative, said mechanism being normally out of operation, and a control member for throwing said mechanism into operation.
7. In combination with an internal combustion engine, means for supplying fuel to said engine, 45 a device actuatable to render the engine inoperative, mechanism responsive to the amount of fuel used by said engine for actuating the device which renders the engine inoperative, said mechanism being normally out of operation, and a control
8. In combination, an internal combustion engine having a carburetor, an intake manifold, and an ignition system, a fuel-supply tank, an auxiliary fuel tank, a pump for drawing fuel from said supply tank through said auxiliary tank and delivering it to said carburetor, connections and a valve selectively operable to connect the upper portion of said auxiliary tank to said intake manifold or to atmosphere, a float in said tank, mechanism actuated by said float and operative when the float reaches a predetermined point in downward movement to render the ignition system inoperative, and a second valve actuated by said 15 float when it reaches a predetermined point in upward movement to close communication between the auxiliary tank and said first named valve.
9. The invention set forth in claim 8, with the 20 addition that said mechanism comprises a switch, and a second switch jointly operable with said first named valve and connected in parallel with the other switch.
10. In combination with an internal combustion engine having an ignition system, means for supplying fuel to said engine, a switch actuatable to render said ignition system inoperative, a control member, mechanism operable under the control of said control member and responsive to the 25 amount of fuel used by the engine for actuating said switch to render the ignition system inoperative, and a second switch jointly operable with said control member and connected in parallel with the other switch.
11. In combination with an internal combustion engine having an ignition system and a carburetor provided with a float bowl, a fuel-supply tank, a conduit connecting said supply tank with said float bowl and including a pump and a shut-off valve, and mechanism responsive to the amount of fuel used by the engine after said shut-off valve has been closed for rendering the ignition system inoperative.
12. In combination with an internal combustion engine having an ignition system and a carburetor provided with a float bowl, a fuel-supply tank, a conduit connecting said supply tank with said float bowl and including a pump and a shut-off valve, a switch actuatable to render said ignition system inoperative, mechanism responsive to the amount of fuel used by said engine after said valve has been closed for actuating said switch to render the ignition system inoperative, and a second switch jointly operated with said valve and 40 connected in parallel with the other switch.

FRANKLIN W. GAMAGE.
